(57) **CLAIM**

The ornamental design for a carrying case, as shown and described.

DESCRIPTION

FIG. 1 is a top-left perspective view of a carrying case in accordance with our design;

FIG. 2 is a bottom-right perspective view of the carrying case thereof;

FIG. 3 is a front elevational view of the carrying case thereof;

FIG. 4 is a rear elevational view of the carrying case thereof;

FIG. 5 is a left side elevational view of the carrying case thereof;

FIG. 6 is a right side elevational view of the carrying case thereof;

FIG. 7 is a top plan view of the carrying case thereof; and,

FIG. 8 is a bottom plan view of the carrying case thereof. The broken lines having consistent dash lengths (dash-dash-dash) represent portions of the carrying case that form no part of the claimed design.

1 Claim, 6 Drawing Sheets
